UNITED STATES PATENT OFFICE

ALBERT BULLOCK, OF LOS ANGELES, CALIFORNIA

POWER DEVICE

Application filed July 14, 1930. Serial No. 467,702.

My invention relates to a device for transforming rotary motion to reciprocating motion and relates particularly to a reciprocating device which may be used for pumping oil wells. My invention departs from the crank principle of reciprocating a member, such as a pump piston, by means of a rotating crank. In this old method common to reciprocating pumps, the pressure exerted against the piston by the crank and the speed of the piston both vary in accordance with the position of the crank by which the piston is operated. My invention provides a means whereby the speed of the piston or reciprocating parts is maintained constant throughout the length of the stroke, and the pressure applied to the reciprocating parts is also kept substantially constant throughout the stroke thereof.

It is an object of my invention to provide an elongated rack having inwardly facing teeth, and a pinion gear adapted to engage the rack, this pinion gear being laterally movable and being provided with means for moving it from one side to the other of the elongated rack during reciprocation of the rack by means of the pinion.

A further object of the invention is to provide a reciprocating or pumping device of the above character having means for holding the pinion in one or the other of its extremes of lateral movement so that the pinion will be maintained in proper operating engagement with the side teeth of the rack, and it is a further object of the invention to provide an eccentric support for the pinion so constructed that the pressure of the pumping action thereagainst will hold the pinion in a lateral position so as to positively engage the side teeth of the rack.

A further object of the invention is to provide locking means, preferably of toggle form, for holding the pinion in engagement with the side teeth of the rack, and to provide an engagement means which will move with the rack and engage the locking means in a manner to operate the same.

A further object of the invention is to provide a reciprocating device having a frame provided with a vertical guide in which an

elongated rack is slidably carried, and a laterally movable gear mechanism adapted to engage the rack and to move back and forth from side to side of the rack as the rack is reciprocated upwardly and downwardly by the gear mechanism. In this preferred form of the invention I prefer to employ a gear mechanism consisting of a pinion which engages the rack, and a train of speed reducing gears for turning the pinion, this train of speed reducing gears being carried in a laterally movable structure which also supports a power device, such as a motor, for delivering power to the mechanism.

Further objects and advantages of the invention will be made evident throughout the following part of the specification.

Referring to the drawings, which are for illustrative purposes only,

Fig. 1 is a side elevation of a preferred form of my invention.

Fig. 2 is a horizontal cross section, drawn to reduced scale, on a plane represented by the line 2—2 of Fig. 1.

Fig. 3 is an enlarged cross section on a plane represented by the line 3—3 of Fig. 1, showing the gear mechanism of my invention.

Fig. 4 is a fragmentary section on a plane represented by the line 4—4 of Fig. 3, showing the locking mechanism of the invention in locked position during downward movement of the rack member of the invention.

Fig. 5 is a fragmentary cross section similar to Fig. 4, showing the locking mechanism in unlocked position during the upward movement of the rack member.

Fig. 6 is an enlarged elevational view of the eccentric supporting means for the pinion which drives the rack member of the invention.

Fig. 7 is an elevational view of a form of my invention employing a cam for positively moving the pinion into engagement with opposite sides of the rack member.

Fig. 8 is a cross section on a plane represented by the line 8—8 of Fig. 7.

Fig. 9 is an elevational view showing a form of my invention in which the pinion is held in engagement with the rack by pressure of the rack against the pinion, which pressure

is transmitted to an eccentric support by which the pinion is carried.

In the form of my invention shown in Figs. 1 to 6 I employ a frame structure 11 consisting of a square base 12 and four upright legs 13, which slope inwardly so as to define a rectangular pyramid. The upper ends of the legs 13 are secured to a cap plate 14 from which guide members 15 and 16 extend downwardly, these guide members preferably consisting of structural channels with the webs thereof faced inwardly. The lower ends of the members 15 and 16 are reinforced by means of braces 17 the ends of which are secured to the legs 13 by means of bolts, as indicated at 18. As shown in Figs. 1 and 3, supporting plates 20 are secured on opposite sides of the guide members 15 and 16 by use of cap screws 21, these plates 20 being positioned just below the center of the guides 15 and 16. Secured on the upper faces of these plates 20 are bearing blocks 22 consisting of upper and lower cooperating halves 23 and 24, the lower parts 24 being secured by means 25 of bolts 25 to the plates 20, and the upper parts 23 being secured to the lower parts 24 by cap screws 26, as shown in Fig. 6. Within the bore 27 of each bearing block 22 is an eccentric member 28 which consists of a cylindrical body of external diameter to rotate in the bore 27 and having an eccentric opening 30 therein in which a bearing 31 is placed to receive a shaft 32 which extends through both bearing blocks 22 and carries thereon a pinion 33. This pinion 33 is disposed between the guides 15 and 16 and is adapted to engage a rack member 34 which slides vertically within the guides 15 and 16. The rack member 34 is in the form of an elongated internal gear and, as best shown in Fig. 1, has parallel substantially straight sides 35 and 36 on which side teeth 37 and 38 are respectively formed. The member 34 also includes upper and lower semi-circular ends 40 and 41 which are provided with end teeth 42 and 43 faced inwardly and placed so as to define semi-circles, the side teeth 37 and 38 and the end teeth 42 and 43 constituting an elongated loop or elongated internal gear. The outer faces 50 of the side portions 35 and 36 are provided with cast iron plates 44 which make bearing engagement with the inner faces of the guides 15 and 16.

Ends 45 of the shaft 32 project through and beyond the eccentric members 28 and have relatively large gears 46 of the same diameter secured thereon. These gears 46 are enclosed by the hollow leg portions 47 of a gear casing 48, this gear casing 48 being preferably formed of upper and lower cooperating halves 50 and 51. The gear casing 48 includes at the rightward ends of the side or leg portions 47 a hollow wall structure 52 which supports an intermediate shaft 53 carrying small pinions 54 at the ends thereof.

in engagement with the gears 46. On the center of the shaft 53 a large gear 55 is mounted, and this gear 55 is driven by a pinion 56 carried on a shaft 57 having an end 58 projecting from the casing so that a pulley 60 may be mounted thereon, which, as shown in Fig. 1, is driven by a belt 61 extending from the pulley 62 of a motor 63 mounted on the upper portion of the casing 48. The gears 46, 54, 55, and 56 constitute a reduction gear train for reducing down from the speed of the motor to the proper speed of rotation for the pinion 33; therefore, when the motor is turned on, the pinion 33 will be driven at slow speed but with comparatively large torque. As shown in Figs. 3, 4, and 5, locking means 64 is provided for holding the supporting means for the pinion 33 in such position that the pinion will engage a side of the rack member 34. By supporting means for the pinion 33 is meant those parts for carrying the pinion 33 in position for operation, and includes the shaft 32, the bearings 31, and the eccentrics 28. The locking means 64 consists of metal rings 65 surrounding the shaft 32 in position between the eccentrics 28 and the ends of the pinion 33, and toggle links 66 which are hinged to the rings 65 at 67 and to pins 68 carried by lugs 70 on the outer face of the guide member 15. In Fig. 4 a toggle link 66 is shown in operative position so as to hold the pinion 33 against the right side portion 37 of the rack member 34 and in engagement with the teeth 38 thereof. It will be noted that the pin 67 is disposed below a horizontal line extended through the centers of the pin 68 and the gear 33 so that the thrust exerted against the gear 33 in leftward direction will not cause the toggle to collapse but will hold the stops 72 and 73 of the ring 65 and the link 66 tightly together. In Fig. 4 the gear 33 is rotating in the clockwise direction indicated by the arrow 74, and the rack member 34 is moving downwardly, the upper end teeth 42 thereof approaching the upper portion of the pinion 33. As the teeth of the pinion 33 come into engagement with the first part of the end teeth 42, an arm or dog 75 projecting rightwardly from the ring 65 is engaged by an actuating pin 76 mounted near the upper end of the rack member 34, thus rotating the ring 65 in clockwise direction so as to cause the toggle pin 67 to swing upwardly, whereupon the toggle formed between the ring 65 and the link 66 may collapse into substantially the positions shown in Fig. 5, in which the rack member 34 is being carried upwardly or through a lifting stroke by the pinion 33.

The eccentric 28 is so designed that pressure exerted thereagainst during proper operation of the device will hold the pinion 33 in engagement with one side or the other of the rack member 34. In Fig. 6 the axis of the eccentric 28 is designated by the point 77,

and the axis of the opening 30 and the shaft 32 extending therethrough is indicated by the point 78. When the eccentric 28 is partially rotated, the axis 78 will traverse an arc 80 so as to move into the position 81, whereupon the shaft 32 will then assume the position indicated by the dotted lines 82. The rotation of the eccentric 28 is limited by a stop member 83 carried in the bearing block 22 and adapted to engage shoulders 84 and 85 formed on the eccentric 28. The distance D between the points 78 and 81 is equal to the distance through which the pinion 33 must move laterally across the end teeth 42 of the rack member from engagement with the side teeth 38 to engagement with the side teeth 37. When the pinion 33 is in the position in which it is shown in Fig. 4, both of the eccentrics 28 are in the position shown in Fig. 6, the shaft 32 being in such position that its axis coincides with the point 78. As the pinion 33 engages and rolls leftwardly across the upper end teeth 42, the axis of the shaft 32 is swung upwardly and then downwardly in leftward direction through the path indicated by the arc 80 into the position designated by the point 81, the eccentrics 28 rotating at this time so as to cause engagement of the shoulder 85 with the stop 83.

During the lifting stroke of the rack member 34, a reaction or thrust is exerted downwardly by the teeth 37, and a lateral thrust in rightward direction is produced by the engagement of the sloping faces of the pinion and rack teeth, these teeth being preferably formed with a 20° engagement or thrust angle. The eccentric is so designed that the component of the vertical and lateral forces above mentioned will lie along a line such as indicated by the arrow 86 which, when extended through the point 81, will lie to the left of the center 77 of the eccentric 28, thus producing a force tending to rotate the eccentric in anti-clockwise direction and to hold the pinion 33 positively in engagement with the leftward teeth 37 of the rack 34. In view of the fact that the load on the eccentric is constant during the lifting stroke of the rack member 34, the action of the eccentric is sufficient to hold the pinion 33 in engagement with the leftward teeth 37 of the rack, but it is evident that locking means of the same character as the locking means 64 may be employed to lock the pinion 33 in leftward position as well as in rightward position. During the upward stroke of the rack member 34, the load may be indeterminate; therefore, the use of the locking means 64 is advisable. In Fig. 5 I show a disengaging pin 87 at the lower end of the rack member 34, which engages the lug 75 of the toggle mechanism when the pinion 33 engages and rolls rightwardly across the lower end teeth 43, causing the ring 65 to rotate in leftward or anti-clockwise direction so as to swing the toggle arm 66 downwardly from the position in which it is shown in Fig. 5 into the position in which it is shown in Fig. 4. In this manner I have provided the device with means for positively actuating the locking means for holding the pinion 33 in engagement with side teeth of the rack member or oval gear.

As shown in Fig. 1, a pump shaft 90 is connected to the lower end of the rack member 34 by means of a cushioned connector 91 which consists of a cylindrical frame 92, the upper end of which is hinged at 93 to the lower end of the rack member 34, and the interior of which carries a body of resilient material 94, such as rubber. A plate or piston 95 is secured to the upper end of the shaft 90 so as to rest on the upper face of the resilient body 94 and to absorb shocks which may be incurred at the ends of the strokes of the rack member 34. Through a similar cushioned connector 96, the upper end of the rack member 34 is connected to a counterbalance cable 97 which extends over a pulley 98 and has a counterweight 100 secured to the outer end thereof.

The frame 11 is supported on foundation blocks 101 by means of rubber cushions 102 contained in cup-shaped members 103 into which plunger members 104 project downwardly from the corners of the base structure 12 of the frame 11.

The gear casing 48 is held in horizontal position and prevented from rotating on the shaft 32 by means of a link 105 which is secured to a clevis 106 mounted on the base structure 12 of the frame 11 and is secured to a bracket 107, which projects rightwardly from the casing 48, by means of a cross pin 108.

In Figs. 7 and 8 I show in simple manner a form of my invention in which a pinion 110 is positively moved from side to side of an elongated internal gear or rack member 111. In this form of the invention the rack member is carried in vertical side bars 112 which project upwardly from a base block 113. By means of horizontally projecting pins or shafts 114, vertical arms 115 are extended upwardly on each side of the rack member 111, these arms having bearings 116 and 117 at the upper ends thereof. The pinion 110 is carried on a shaft 118, the forward end 120 of which is supported in the bearing 116, and the rearward portion 121 of which shaft 118 projects through a sleeve 122 which is carried in the bearing 117. The inner end of the sleeve 122 is provided with a cam 123, and the outer end thereof is provided with a gear 124. On the side members 112 cam followers in the form of rollers 125 and 126 are mounted in position to be engaged by the circular cam 123 as such cam is rotated, whereby to cause the shaft 118 to swing from one side to the other of the rack member 111 in accordance with the reciprocation there-

of. To rotate the cam 123 in properly timed relationship to the rotation of the pinion 110 I provide a gear train consisting of the gear 124, a small gear 127, a larger gear 128 secured to the gear 127, and a smaller gear 130 secured to the shaft 118, this arrangement of gears accomplishing the desired reduction of speed for turning the cam 123 slowly as compared to the rotation of the pinion 110. The relative speeds of the cam 123 and the pinion 110 depend on the ratio existing between the pinion 110 and the rack member 111. If a one-to-one ratio between the pinion 110 and the rack 111 is established, the cam 123 will rotate at the same rate of speed as the shaft 118 and in such instances may be secured directly thereto. When the ratio of the pinion 110 to the rack 111 is increased, the ratio of the rotation of the cam 123 to the pinion 110 is decreased in proportion inverse to the ratio of the pinion to the rack member. As a means for rotating the shaft 118 I have shown a pulley 132, and projecting upwardly from the rack member 111 I show a rod 133 which projects into a counterbalance cylinder 134 mounted at the upper ends of the side members 112, and carries a piston 135 thereon. As the piston 135 moves downwardly, it compresses fluid, such as air, within the lower part of the cylinder 134, thus building up a counterbalancing pressure against the under face of the piston 135, which pressure resists downward movement of the rack 111 and the parts to which such rack is attached.

In order that the cam 123 may be properly timed with the operation of the pinion 110 and the rack 111, I have found that the teeth in the respective members 110 and 111 must be proportioned in accordance with a fixed rule, and for the design of a reciprocating mechanism of the character shown in Fig. 7, I have developed the following formula:

$$Tr = RN + Te - (Te - N)$$

in which

Tr = teeth in rack

Te = teeth in end gears

N = number of teeth in pinion

R = ratio of turns of pinion to reciprocations of rack.

In the use of this formula let it be assumed that the ratio of the pinion to the rack is four-to-one, so that the pinion 110 makes four revolutions for one complete reciprocation of the rack. In the pinion there are sixteen teeth; therefore, the rack should have the equivalent of sixty-four teeth. The curved end portions 140 each have nine teeth so as to form halves of an eighteen-toothed gear. Owing to the fact that the pinion 110 rotates through only a small part of a revolution during the time it is traversing the circular ends of the rack 111, eighty teeth must be employed, whereas from a cursory

consideration of the problem it would appear that the number of teeth in the rack would be four times the number of teeth in the pinion, or sixty-four. Using the same formula, thirty-two teeth would be required in the rack of a device of the above character having a one-to-one ratio and a pinion of sixteen teeth and end gears of nine teeth each. In the form of my invention shown in Fig. 9, I show a pinion 150 supported by a laterally extending shaft 151 which projects into the eccentric opening 152 of an eccentric member 153 carried in a bearing member 154 which is secured to guide members 155 by means of bolts 156. A rack member 157 is supported in the guide members 155 and is connected to a continuous load by means of a shaft or rod 158 which projects downwardly from the lower end thereof. In this device the pressure exerted against the rack is always in downward direction, with the result that no matter which way the eccentric 153 may be turned the result of the downward pressure and the pressure exerted by the teeth will always produce a rotation of the pinion 150 into engagement with a cooperating side of the rack 157. As shown in Fig. 9, the eccentric 153 is rotated rightwardly so that downward pressure thereagainst tends to hold the shaft 151 and the pinion 150 in rightward direction. The rotation of the pinion 150, being in rightward direction, as indicated by the arrow 160, causes the teeth thereof to traverse the upper end of the rack in leftward direction so as to swing the center point 161 of the shaft 151 and the pinion 150 over to the position indicated by the point 163, at which time the teeth of the pinion 150 will be in engagement with the leftward side of the rack 157 and will move the rack upwardly, the pressure of the rack and of the interengaging teeth then causing the pinion 150 to remain in leftward position until the rack is raised to its full extent to bring the teeth at the lower end of the rack into engagement with the pinion 150, at which time the pinion 150 will move rightwardly into a position for engagement with the rightward side of the rack 157. In this form of the invention I have illustrated how my invention may be practiced without external or auxiliary means for moving the pinion from side to side of the reciprocating rack, employing only the normal pressure encountered in the operation of the device for accomplishing this movement and maintaining the pinion in engagement with the sides of the rack member.

Although my invention has been initially designed for use as a pumping jack for pumping of oil wells, it is recognized that the reciprocating and rotary parts thereof may be employed in many other mechanisms. Although I have herein shown and described simple and operative embodiments of my in-

vention, it is recognized that certain parts or elements thereof are representative of other parts, elements, or mechanisms which may be employed in substantially the same manner

5 to accomplish substantially the same results; therefore, it is to be understood that my invention is not to be limited to the details disclosed herein but shall be accorded the scope of the following claim.

10 I claim as my invention:

A power device of the character described, including: a reciprocating rack member having teeth arranged to define an elongated loop including side teeth defining substantially straight lines and end teeth substantially defining semi-circles connecting across the ends of said substantially straight lines; slide means supporting said rack member; a pinion engaging the teeth of said rack member; a pinion support for supporting said pinion in operative position, said pinion support being movable in a direction lateral with respect to the line of movement of said rack member so as to permit movement of said pinion by said end teeth from one side to the other of said rack; and means operative in response to pressure of said rack member against said pinion for holding said pinion support in its extreme positions so as to hold said pinion in engagement with said side teeth of said rack member after movement of said pinion by said end teeth.

In testimony whereof, I have hereunto set my hand at Los Angeles, California, this 9th
35 day of July, 1930.

ALBERT BULLOCK.
